UNITED STATES PATENT OFFICE

141,740

DESIGN FOR AN INLAY PUZZLE PLAQUE

Samuel A. Karlin, Chicago, Ill.

Application March 24, 1945, Serial No. 118,672

Term of patent 7 years

(Cl. D34—15)

To all whom it may concern:

Be it known that I, Samuel A. Karlin, a citizen of the United States, residing at Chicago, county of Cook, and State of Illinois, have invented a new, original, and ornamental Design for an Inlay Puzzle Plaque, of which the following is a specification, reference being had to the accompanying drawing, forming a part thereof, in which:

Figure 1 is a front elevational view, and Figure 2 is a side elevational view of an inlay puzzle plaque, showing my new design.

I claim:

The ornamental design for an inlay puzzle plaque, substantially as shown.

SAMUEL A. KARLIN.
